ABSTRACT

A process of converting tertiary amines to secondary amines is described comprising reacting the tertiary amine with a peracid to form the N-oxide which is converted to the secondary amine in the presence of an alkali metal and liquid ammonia.

10 Claims, No Drawings

PROCESS FOR PREPARATION OF SECONDARY AMINES FROM TERTIARY AMINES

This invention relates to a novel process for producing secondary amines from tertiary amines.

One aspect of the present invention relates to a novel process for the protection and preparation of secondary amines from tertiary amines through the preparation of an intermediate N-oxide which is converted to the secondary amine.

A further aspect of the present invention is to convert tertiary amines wherein the nitrogen is substituted with a benzyl, allyl or propargyl group to the corresponding secondary amine by the cleavage of such group.

Yet another aspect of the present invention relates to an improved process for scission of a benzylic type bridgehead carbon-nitrogen bond in a ring system to convert the tertiary nitrogen to a secondary amine.

An additional aspect of the present invention relates to converting compounds containing ring systems, such as appropriate benzquinolizines (including emetines), benzindolizines, indolquinolizines and indolindolizines to secondary amines at the carbon-nitrogen bridgehead, in yields higher than heretofore obtainable with prior art processes.

These and other aspects of the present invention will be apparent from the following description.

In its broadest aspect, the process of the present invention comprises reacting a tertiary amine with an oxidizing agent such as a peracid to form the N-oxide of the selected tertiary amine and then reacting the N-oxide with an alkali metal in the presence of liquid ammonia to form the secondary amine.

The tertiary amines that are particularly useful in the process of the present invention are those having either (a) a substituent linked directly to the N-atom selected from the class consisting of allyl, dimethyl allyl, propargyl, benzyl or substituted benzyl or (b) a benzylic type bridgehead carbon-nitrogen structure. The preferred secondary amines obtained by the process of the present invention have the following structural formula:

wherein R¹ and R² are selected from the class consisting of an aliphatic radical and an alicyclic radical, which radicals are not subject to cleavage from the nitrogen to which it is linked under the process conditions of the present invention and which radicals do not undergo any change in chemical structure under the process conditions for converting the tertiary amine to a secondary amine and/or obtaining a substituted aralkyl compound; R¹ plus R² may be joined to form with the N atom a non-aromatic type heterocyclic moiety having up to nine carbon atoms in the ring which may optionally include one additional hetero atom in the ring selected from the class consisting of oxygen and nitrogen. The hetero ring is either saturated or it may contain a non-allylic double bond; n is a whole number

which is 1 or 2; A represents a fused benzene nucleus or fused indole nucleus attached through its 2-3 position to the nitrogen containing ring; X represents one or more substituents selected from the group consisting of hydrogen, (lower)alkyl, lower alkoxy, methylene dioxy, hydroxy, hydroxy (lower)alkyl, lower alkoxy-isoquinolinyl methyl, 2-acetylisoquinolinyl methyl, 2-(lower)alkyl-isoquinolinyl methyl; Z and Z¹ are selected from the group consisting of hydrogen and lower alkyl.

As used herein "lower alkyl" means a straight or branch chain hydrocarbon radical having C₁-C₆ carbons are exemplified by methyl, ethyl, propyl, isobutyl, sec butyl, hexyl. The term "lower alkoxy" means a straight or branch chain radical having C₁-C₆ carbons (e.g. methoxy, ethoxy, butoxy, isobutoxy, etc.). Examples of R¹ and R² joined together to form a heterocyclic radical are piperidino, pyrrolidino, piperazino, morpholino, hexamethylenimino, decahydroquinoline, benzazocine, 2,3,6,7-tetrahydro-1H-azepine, etc. Illustrative of aliphatic radicals defined by R¹ and R² are straight or branch chain alkyl groups having 1 to 12 carbon atoms, an non-allylic alkenyl group having 4 to 12 carbon atoms (e.g. 3-pentenyl) or a non-allylic, non-conjugated alkadienyl group having 6 to 12 carbon atoms (e.g. 3,6-decadienyl). Illustrative of alicyclic radicals are cycloalkyl groups having four through ten ring carbon atoms (e.g. cyclobutyl, cyclopentyl, cyclohexyl, cyclooctyl), non-allylic cycloalkenyl groups having seven through ten ring carbon atoms (e.g. 4-cycloheptenyl), an aryl radical having from six to ten ring carbon atoms (e.g. phenyl, naphthyl), an aryl(lower)alkyl radical (e.g. β -phenylethyl, α -phenylpropyl). The foregoing radicals may contain one or more substituents such as hydroxy, (lower)alkoxy.

The process of the present invention is carried out by treating compound III with a peracid at a temperature between +32° and 40°C. to produce the corresponding N-oxide which is then treated with an alkali metal in liquid ammonia to produce the secondary amine as shown in the following equations:

wherein R³ is selected from the group consisting of allyl, dimethyl allyl, propargyl and unsubstituted or substituted benzyl. The treatment of IIIa is preferably carried out in the presence of a proton donor. The formation of I is via N-OH intermediate. In the absence of a proton donor (i.e. an alcohol) the reaction of IIIa with the alkali metal in liquid ammonia leads to the formation of a mixture of IIIb and I.

In the same manner the secondary amines defined by formula II are prepared by starting with a bridgehead nitrogen compound shown in the following formula:

Examples of suitable peracids that may be used in the process of the present invention are m-chloroperbenzoic acid, monoperphthalic acid, per acetic acid, per formic acid, per benzoic acid, per malic acid, trifluoroperacetic acid, hydrogen peroxide. Suitable alkali metals include lithium, sodium and potassium. The proton donor may be any lower aliphatic alcohol or an arylalkanol such as 1-methoxy-2-propanol, methanol, ethanol, isopropanol, benzyl alcohol, etc.

The following examples illustrate the preparation of representative compounds using the process of the present invention.

EXAMPLE 1

1,3,4,6,7,11b-Hexahydro-9,10-Dimethoxy-2H-Benzo[a]Quinalizine 5-Oxide Hydrochloride

The compound 1,3,4,6,7,11b-hexahydro-9,10-dimethoxy-2H-benzo[a]quinolizine (R. Child and F. Lee Pyman, JCS 36 [1931]) (5 g. 2.07×10^{-2} moles) in MeOH (40 ml) is treated, dropwise, at -10°C . with ethereal monoperphthalic acid solution (38 ml., 0.65 molar, 2.47×10^{-2} moles) and the resultant solution is stored at 0°C . overnight. Excess 10% NaOH solution is added which results in formation of two layers. The upper ethereal layer is washed with water and discarded. The aqueous layer is extracted with CHCl_3 three times. The extracts are washed with brine, dried (K_2CO_3) and stripped. The residue, a pale green oil is treated in tetrahydrofuran with a slight excess of isopropanolic hydrogen chloride to give a crystalline precipitate of the product. Recrystallization from chloroform-acetone provides 4.5 g. of the titled product, m.p. $205^{\circ}\text{--}212^{\circ}\text{C}$. decomposition.

Analysis: Calculated for $\text{C}_{15}\text{H}_{21}\text{NO}_3 \cdot \text{HCl}$: C, 60.09; H, 7.40; N, 4.67; Cl, 11.83

Found: C, 59.84; H, 7.26; N, 4.65; Cl, 11.82

EXAMPLE 2

1,2,3,5,6,10b-Hexahydro-8,9-Dimethoxypyrrolo[2,1-a]Isoquinoline-4-Oxide, Hydrochloride

Using the method of Example 1, 1,2,3,5,6,10b-hexahydro-8,9-dimethoxypyrrolo[2,1-a]isoquinoline [R. Child and F. Lee Pyman, JCS 36 (1931)] is converted to the title compound, m.p. $188.5^{\circ}\text{--}192^{\circ}\text{C}$. decomposition.

Analysis: Calculated for $\text{C}_{14}\text{H}_{19}\text{NO}_3 \cdot \text{HCl}$: C, 58.84; H, 7.05; N, 4.90; Cl, 12.41

Found: C, 58.93; H, 7.07; N, 5.14; Cl, 12.45

EXAMPLE 3

1,2,3,4,5,6,7,8-Octahydro-10,11-Dimethoxy-3-Benzazecine Hydrochloride

The compound prepared in Example 1 (2 g., 7.6×10^{-3} moles) in THF (20 ml.) is added to a stirred solution of NH_3 (500 ml.) containing 1-methoxy-2-propanol (3 ml., 3×10^{-2} moles) Lithium (260 mg., 3.7×10^{-2} moles) is added portionwise and the deep blue solution vigorously during a further 6 minutes after completion of the addition. Excess lithium is decomposed by water and the reaction mixture diluted cautiously with warm water. The product isolated by CHCl_3 extraction is purified by filtration in ether through a short column of Woelm Al_2O_3 Grade I basic. The hydrochloride is obtained by addition of isopropanolic hydrogen chloride to the eluate and recrystallized from acetonehexane to give 1.2 g. of the title compound, m.p. $125^{\circ}\text{--}126^{\circ}\text{C}$. identical with an authentic sample [J. P. Yardley, R. W. Rees and H. Smith, J. Med. Chem., 10, 1088 (1967)].

EXAMPLE 4

Using the compound of Example 1 as a starting material, Example 3 was repeated except that the 1-methoxy-2-propanol was omitted and the reaction time is reduced from 6 minutes to $2 \frac{1}{2}$ minutes. There is obtained after dilution with warm water and CHCl_3 extraction a crystalline residue, m.p. $135^{\circ}\text{--}143^{\circ}\text{C}$. shown by glc to be a mixture of two major components. Column silicone (Floro) QF-1 linear program $180^{\circ}\text{--}250^{\circ}$, 5 minutes at 180° , then at $8^{\circ}/\text{min}$. 59% mixture retention time after 4.6 minutes and 14 minutes 36% mixture (N-OH compound). Mass spectograph indicates a mixture with molecular ions at 249 (title compound of Example 3) and 265

(N-OH compound of Example 3).

EXAMPLE 5

2,3,4,5,6,7-Hexahydro-9,10-Dimethoxy-1H-3-Benzazonine Hydrochloride

Using the method of Example 3, 1,2,3,5,6,10b-hexahydro-8,9-dimethoxypyrrolo[2,1-a]isoquinoline-3-oxide is converted to the title compound. Identity is established by comparison with an authentic sample [J. P. Yardley et al. J. Med. Chem., 10, 1088 (1967)]. The starting N-oxide was prepared in accordance with the procedure of Example 1.

EXAMPLE 6

1',2'-Secoemetine

Benzoyloxycarbonylemetine [J. P. Yardley et al. J. Med. Chem., 10, 1088 (1967)] 14.3 g. (2.32×10^{-2} moles) in methanol (60 ml.) is treated, dropwise, at -10°C . with 58.5 ml. ethereal monoperphthalic acid (0.585 molar 3.5×10^{-2} moles) and the mixture is kept at $0^{\circ}\text{--}5^{\circ}\text{C}$. overnight. This mixture is basified strongly with 10% aqueous NaOH solution and extracted with CHCl_3 (five times). The CHCl_3 extracts are washed with brine, dried (K_2CO_3) and evaporated to give the crude oily N-oxide (12 g.). The oily N-oxide (5 g., 7.7×10^{-3} moles) is placed in tetrahydrofuran (25 ml.) and added to NH_3 (1.5 L) containing 1-methoxy-2-propanol (4.8 ml., 419×10^{-2} moles). Lithium (260 mg., 3.7×10^{-2} moles) is added portionwise to a permanent blue coloration. Acetic acid (2.22 g., 2.1 ml.

3.5×10^{-2} moles) is added and the solution again titrated to a permanent blue coloration. 200 mg. of lithium is added, after 6 minutes the reaction mixture is diluted with hot water and extracted with CHCl_3 . The chloroform extracts are washed with brine, dried (Na_2SO_4) and the stripped residue in ether is charcoaled (Norite) and treated with an excess of isopropanolic hydrogen chloride. The precipitate crystallizes from acetone to give 3 g. 1',2'-secoemetinehydrochloride, m.p. 234°-237°C.

Conversion of a portion to the bis hydroiodide [cf. J. P. Yardley et al., *J. Med Chem.*, 10, 1088 (1967)] confirmed its identity.

EXAMPLE 7

N-Allyl trans Decahydroquinoline Hydrochloride

Trans decahydroquinoline (20 g., 1.44×10^{-1} moles), allyl chloride (16 ml., 1.96×10^{-1} moles), triethylamine (18 ml., 1.96×10^{-1} moles) and acetonitrile (200 ml.) are stirred at room temperature under nitrogen overnight. The reaction mixture is evaporated in vacuo and the residue distributed between ether and saturated NaHCO_3 solution. The ether layer is washed with water (twice), brine, and dried (Na_2SO_4). The product is filtered in ether through a Woelm Al_2O_3 (Grade I basic) column and eluted with the same solvent. Treatment of the eluate with an excess of isopropanolic hydrogen chloride and recrystallization of the precipitate from acetone-hexane gives 14 g. of the title compound m.p. 133°-135°C.

Analysis: Calculated for $\text{C}_{12}\text{H}_{22}\text{NCl}$: C, 66.79; H, 10.28; N, 6.49; Cl, 16.43

Found: C, 66.71; H, 10.16; N, 6.45; Cl, 16.15

The free base (clear oil) is regenerated from 8 g. of the hydrochloride by treatment with aqueous K_2CO_3 solution extraction into ether, washing with brine and drying (Na_2SO_4). NMR (CDCl_3) shows a complex vinylic resonance (3H) in the range 4.9-6.35 ppm.

The N-allyl trans decahydroquinoline (5.0 g., 2.8×10^{-2} moles) is placed in methanol (25 ml.) and is treated, dropwise at -20°C. during 1 hour with 94 ml. 0.65N monoperphthalic acid solution in ether (3.05×10^{-2} moles). After one further hour during which the reaction mixture is allowed to warm to room temperature, excess aqueous 10% NaOH is added. The ether layer is separated, washed with water, and discarded. The combined aqueous layers are extracted (three times) with CHCl_3 , washed with brine, dried (Na_2SO_4) and stripped at 20°C. to give N-allyl trans dodecahydroquinoline N-oxide, a solid crystalline product (4.5 g.). The NMR shows a complex vinylic resonance (3H) in the range 5.2-6.5 ppm.

EXAMPLE 8

N-allyl decahydroquinoline N-oxide (2.0 g., 1×10^{-2} moles) prepared in accordance with the procedure of Example 7 is placed in NH_3 (1 L) containing 1-methoxy-2-propanol, 4 ml. (4×10^{-2} moles), is treated with lithium (360 mg., 5.2×10^{-2} moles) following by a further 6 ml. (6×10^{-2} moles) of the alcohol. This mixture is stirred until white (ca. 20 minutes), then diluted with hot water and extracted with CHCl_3 (twice), washed with brine, dried (Na_2SO_4) and stripped; the residue is filtered in ether through Woelm Al_2O_3 (10 g.) and eluted with ether to give trans decahydroquinoline (1 g.), m.p. 45°-47°C. (70% yield) identical with an authentic sample.

EXAMPLE 9

1,2,3,4,5,6-Hexahydro-6 α ,8,11-Trimethyl-2,6-Methano-3-Benzazocine

Dl-1,2,3,4,5,6-Hexahydro-cis-6,11-dimethyl-3-(3-methyl-2-butenyl)-2,6-methano-3-benzazocine-8-methanol (700 mg., 2.34×10^{-3} moles) is placed in methanol (7 ml.) and stirred at -20°C. during the dropwise addition of ethereal monoperphthalic acid (6 ml., 0.46 molar, 2.76×10^{-3} moles). The mixture is stirred for a further 3 hours during which time the reaction mixture is allowed to attain room temperature. The mixture is then basified with 10% NaOH solution, washed with ether and the ether layer, after a water backwash, discarded. The aqueous layers are extracted (thrice), the organic layers washed with brine, filtered to clarify the solution and stripped to give a residue of the crude N-oxide (600 mg.).

The crude product (500 mg.) in THF (30 ml.) is added to a freshly distilled NH_3 (180 ml.), treated with 1-methoxy-2-propanol, followed by an excess of lithium. After 8 minutes the mixture is diluted with hot water and extracted with CHCl_3 (twice). The organic layer is washed with brine, stripped and filtered in ether through a column of Woelm Al_2O_3 . Elution with ether afforded 200 mg. colorless oil homogeneous by thin layer chromatography (tlc) (SiO_2 system CHCl_3 -saturated NH_3) and R_f identical with that of 1,2,3,4,5,6-hexahydro-6 α ,8,11-trimethyl-2,6-methano-3-benzazocine prepared by an alternative route. The crystalline hydrochlorine m.p. 231°-232°C. was identical with an authentic sample by mixed m.p., IR, Mass spectograph and NMR.

EXAMPLE 10

Trans-2-Benzylcyclohexanol from Trans-2-[α -(4-Methyl-1-Piperazinyl) Benzyl]Cyclohexanol

Trans-2-[α -(4-methyl-1-piperazinyl)benzyl]cyclohexanol (4.0 g., 1.39×10^{-2} moles) in THF (60 ml.) is added at 0°-5°C to a solution of monochloroperbenzoic acid (85%, 5.7 g., 2.8×10^{-2} moles) during 10 minutes and the solution stored at 5°C. overnight. The reaction mixture is filtered through a Woelm basic Al_2O_3 column (Grade I) built in CHCl_3 and eluted with chloroform-methanol (3:1) to give 4.5 g. of white solid (mass spectrum shows an $M^+ + I$ ion at 321 for a bis N-oxide), 4.4 g. of the above product as a vigorously stirred suspension in THF (40 ml.)—liquid ammonia (1 liter) is treated with excess lithium (230 mg., 3.3×10^{-2} moles). The mixture is quenched with acetone 30 seconds after the appearance of a uniform blue color. Solvent is removed on the steam bath and the residue acidified with an ice-hydrochloric acid mixture. A crystalline solid separates at this stage and is extracted into ether. The ether phase is washed with water, brine and dried (Na_2SO_4). The residue crystallizes from pentane to give 2.0 g. trans 2-benzylcyclohexanol, m.p. 77°C. (lit. 77°, P. B. Russell, *J. Chem. Soc.*, 1771, [1951]).

Found C, 81.67; H, 9.76. $\text{C}_{13}\text{H}_{18}\text{O}$ requires: C, 82.06; H, 9.54%

EXAMPLE 11

1,2,4,5,6,7,8,9-Octahydro-3H-Azecino [5,4-b]Indole
Using the methods of Examples 1 and 3, 1,2,3,4,6,7,12,12b-octahydroindolo-(2,3-a) quinolizine was converted to the title product.

EXAMPLE 12

When the following tertiary amines are employed in the process of the present invention in Examples 1 and 3;

1. dimethyl allyl amine
2. dihydroxyethyl allylamine
3. dimethyl benzyl amine
4. N-allyl piperidine
5. N-propargyl morpholine
6. diphenyl allyl amine
7. dipropyl benzyl amine
8. N-benzyl-2,3,6,7-tetrahydro-1H-azepine
9. N-methyl,N-[3-pentenyl]-benzylamine
10. N-benzyl,N-methyl-3,6-decadienylamine

the following corresponding secondary amines are produced:

1. dimethyl amine
2. dihydroxyethyl amine
3. dimethyl amine
4. piperidine
5. morpholine
6. diphenyl amine
7. dipropyl amine
8. 2,3,6,7-tetrahydro-1H-azepine
9. N-methyl-3-pentenylamine
10. N-methyl-3,6-decadienylamine

The secondary amines of the present invention are useful intermediates in the preparation of pharmacologically active compounds, such as tertiary amines. For example, the compound of Example 6 has been reported to have amebicidal activity [J. P. Yardley, R. W. Rees and H. Smith, *J. Med. Chem.*, 10, 1088 (1967)]. The benzazocines and benzazonines described herein belong to a class of compounds that exhibit diuretic activity and central nervous system depressant activity.

One of the advantages of the process of the present invention is that it affords a simple and convenient method of cleavage of allylic tertiary amines. The previous claim in the literature by Clemo et al. *J. Chem. Soc.*, 1661 (1948) for allyl amine cleavage in strychnine and strychnidine has been disproved by R. Rees et al. *J. Med. Chem.*, 10, 624 (1967), while E. M. Perry Dissertation Abstracts 16, 1587-1588 (1956), (C.A. 51, 2532g) reports "The best catalytic method of 40 cleaving allylic amines is with a platinum catalyst in methyl alcohol solution. Nevertheless, the extent of 45 cleavage even by this catalytic method is small since hydrogenation of the double bond competes with the cleavage reaction; the saturated amine is resistant to 50 cleavage by this method."

What is claimed is:

1. A process of converting a tertiary amine of the formula:

wherein R^1 and R^2 are each a radical selected from the class consisting of an alkyl group of 1 through 12 carbon atoms, a cycloalkyl group having 4 through 10 ring carbon atoms, phenyl, naphthyl and phenyl(lower)alkyl; R^1 and R^2 when joined together form with the N-atom a member selected from the class consisting of piperidino, pyrrolidino, piperazino, morpholino, hexamethylenimino, decahydroquinolino, and 1,2,3,4,5,6-hexahydro-6,11-dimethyl-2,6-methano-3-benzazocino-8-methanol, said groups defined by R^1 and R^2 being optionally substituted with a member selected from the class consisting of hydroxy and (lower)-alkoxy; and R^3

is a member selected from the group consisting of allyl, dimethyl allyl, propargyl and benzyl; to a secondary amine of the formula:

which comprises reacting said tertiary amine with an organic peracid to form the N-oxide of said tertiary amine and reacting said N-oxide with an alkali metal in the presence of liquid ammonia to form the corresponding secondary amine by cleavage of said R^3 group from said tertiary amine, the reaction of said tertiary amine with said organic peracid being carried out at a temperature between about -40°C. and about +32°C.

15 2. A process according to claim 1 wherein said reaction of said N-oxide with said alkali metal in liquid ammonia is carried out in the presence of a proton donor.

3. A process according to claim 1 wherein R^1 and R^2 are joined together to form decahydroquinolyl.

20 4. A process according to claim 1 wherein said tertiary amine is 1,2,3,4,5,6-hexahydro-6,11-dimethyl-3-(3-methyl-2-butenyl)-2,6-methano-3-benzazocine-8-methanol.

5. A process according to claim 1 wherein said tertiary amine is N-allyl dodecahydroquinoline.

25 6. A process of converting a tertiary amine of the formula:

30 wherein:

A represents a fused benzene nucleus or fused indole nucleus attached through its 2-3 position to the nitrogen containing ring; X represents one or more substituents selected from the group consisting of hydrogen, lower alkyl, lower alkoxy, hydroxy, hydroxy(lower)alkyl, lower alkoxyisoquinolinylmethyl, 2-acetylisooquinolinylmethyl, 2-(lower)alkyl-isoquinolinylmethyl; Z or Z' are selected from the class consisting of hydrogen and (lower)alkyl; n is a number selected from 1 to 2; to a secondary amine of the formula:

55 60 which comprises reacting said tertiary amine with an organic peracid to form the corresponding N-oxide of said tertiary amine, said reaction being carried out between -40°C. and about 0°C., and reacting said N-oxide with an alkali metal in the presence of liquid ammonia to form said secondary amine.

7. A process according to claim 6 wherein said reaction of said N-oxide with said alkali metal is carried out in the presence of a proton donor.

8. A process according to claim 7 wherein said proton donor is 1-methoxy-2-propanol.

9. A process according to claim 6 wherein said tertiary amine is benzylloxycarbonylmetine and the secondary amine obtained is 1',2',2'-secoemetine.

10. A process which comprises reacting trans-2-[α -(4-methyl-1-piperazinyl)benzyl]cyclohexanol with an organic peracid to form an N-oxide of said tertiary amine and reacting said N-oxide with an alkali metal in

the presence of liquid ammonia to cleave off trans-2-benzylcyclohexanol.
